UNITED STATES PATENT OFFICE.

ROBERT P. POTTER, OF SOUND BEACH, CONNECTICUT, ASSIGNOR TO THE C. D. POTTER CO., OF STAMFORD, CONNECTICUT, A CORPORATION OF CONNECTICUT.

PEDAL MECHANISM FOR PLAYER-PIANOS.

1,281,295.

Specification of Letters Patent. Patented June 26, 1917.

Application filed December 20, 1916. Serial No. 138,010.

To all whom it may concern:

Be it known that I, ROBERT P. POTTER, a citizen of the United States, and a resident of Sound Beach, in the county of Fairfield and State of Connecticut, have invented a new and Improved Pedal Mechanism for Player-Pianos, of which the following is a full, clear, and exact description.

This invention relates to pedal mechanism adapted to be used in connection with player pianos and the like for operating the bellows or air pump.

The general objects of the present invention are to improve and simplify the construction of mechanism of the character referred to so as to be reliable and efficient in use, comparatively simple and inexpensive to manufacture, and so designed as to comprise a minimum number of parts which are easily and quickly assembled and operate without excessive play, looseness or noise.

More specifically, the invention has for its object to provide a novel form of pedal-carrying frame which is made of rod stock and formed into two L-shaped sections which are coupled together by one of the supporting feet or equivalent means to form a U-shaped frame or structure on the front portion of which the feet are fastened and on which the pedals are hingedly mounted, such feet serving as stops for holding the pedals in place on the frame against lateral movement while allowing free swinging movement incident to the operation of a bellows.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention, and wherein similar characters of reference indicate corresponding parts in all the views,

Figure 1 is a vertical sectional view of the pedal mechanism and bellows, showing the improvements;

Fig. 2 is a front view of the pedal mechanism with the pedal-carrying frame thrown upwardly to inoperative position;

Fig. 3 is an enlarged sectional view through one of the pedals and supporting feet to show the manner of connecting the

sections of the pedal-carrying frame together; and

Fig. 4 is a composite view of the various parts of the mechanism that constitute the invention.

Referring to the drawings, A designates an ordinary bellows or pumping device for a player piano or the like, and B the pedal mechanism for operating the bellows.

The pedal mechanism comprises a pair of pedals 1 which are hingedly mounted at 55 their front ends on a frame 2 and are connected at their upper portions individually to links 3 that are in turn hingedly connected to brackets 4 fastened to the rear part 5 of the bellows A, so that by the up 60 and down swinging movement of the pedals 1, the back part of the bellows will be operated to supply the air desired.

The frame 2 of the pedal mechanism B is, as shown clearly in Fig. 4, composed of two 65 sections of rod or equivalent stock, and each section is bent into L-form and comprises a side arm 6 and a front arm 7. The side arms are adapted to be pivotally connected at 8, as shown in Figs. 1 and 2, to the 70 brackets 9 fastened to the front of the bellows. The front arms 7 are dissimilar as to length and are adapted to aline so as to form an axis on which the pedals swing. The two sections of the frame are, in the 75 present instance, connected together by a coupling element which consists of one of the feet elements 10. The feet elements may be of any desired construction but are shown as consisting of T-shaped castings formed 80 with a central member 11 and a tubular head 12 which has a bore 13 to be received on the front part of the pedal-carrying frame so as to support the frame off the floor on which the members 11 of the feet 85 elements rest. The heads 12 are provided with set screws 14 which extend into the bore 13 and are adapted to bind on the front arms 7 of the pedal-carrying frame, whereby turning of the feet element in the frame 90 and lateral movement are prevented. To 95

hingedly connect the pedals with the frame the under side of each pedal is provided with spaced lugs 15 which are in line with each other and have alining openings 16 so 100 as to be received on the arms 7 of the frame sections 1. These lugs 15 are spaced apart just far enough to snugly receive between

them the head of a foot element, as clearly shown in Fig. 3, so that when the parts are assembled the feet elements serve as stops for limiting the lateral movement of the 5 pedals on the front part of the pedal-carrying frame without, however, interfering with the swinging movement of the pedals. One of the feet elements, as shown clearly in Fig. 3, performs in addition to its function of holding the frame off the floor and of preventing lateral movement of the associated pedal, the function of connecting the two sections of the frame together.

In assembling the parts, each foot element is placed between the lugs 15 of its associated pedal, and these two are then slipped on the long arm 7, and when the parts are in the right position on the arm, the set-screws are tightened. The next pedal 20 with its assembled foot element is slipped on the long arm 7 and then the section of the frame having the short arm is assembled by inserting the short arm in the outer lug 15 of the adjacent pedal, and partly 25 into the associated foot element, as shown in Fig. 3, and then the set-screws are tightened so that the frame sections are thereby rigidly united. If it is desired to change the lateral relation of the pedals the set- 30 screws can be loosened and the pedals shifted toward or from each other, as desired, after which the set-screws are again tightened. A pedal mechanism of the character described is of neat and attractive appearance and at the same time durable and 35 stable and provides for the free operation of the pedals without noise.

From the foregoing description taken in connection with the accompanying drawing, the advantages of the construction and 40 method of operation will be readily understood by those skilled in the art to which the invention appertains, and while I have described the device which I now consider 45 to be the best embodiment thereof, I desire to have it understood that the device shown is merely illustrative and that such changes may be made when desired as are within the scope of the appended claims.

50 Having thus described my invention, I

claim as new and desire to secure by Letters Patent:

1. A pedal mechanism of the class described comprising a frame consisting of two sections each having a front arm, the 55 front arm of one section being longer than the front arm of the other section, a pedal mounted wholly on the long arm, a pedal mounted conjointly on both arms, and tubular elements arranged on the arms to hold 60 the pedals against lateral displacement, one of said elements forming a connector between the sections of the frame.

2. A pedal mechanism of the class described comprising a swinging frame composed of a pair of oppositely disposed elbow sections having respectively alining front arms of different lengths, pedals mounted on the arms, and feet elements mounted on the arms and engaging the 70 pedals to prevent lateral displacement, one of the feet elements forming a connector between the said arms to unite the sections of the frame rigidly together.

3. A pedal mechanism of the class described comprising a swinging frame composed of oppositely disposed L-shaped sections presenting side and front arms, pedals having apertured lugs through which the front arms extend, a T-shaped foot element 80 associated with each pedal having a tubular head set in between the lugs of the associated pedal and through which a front arm extends, and set-screws on the heads for clamping the feet element to the frame. 85

4. A pedal device of the class described, comprising a swinging frame including a front bar, pedals having spaced apertured lugs through which the front bar extends, a foot element disposed between the lugs of 90 each pedal and fastened to the front bar, whereby the feet elements prevent lateral displacement of the pedals.

In testimony whereof I have signed my name to this specification in the presence of 95 two subscribing witnesses.

ROBERT P. POTTER.
